[57] CLAIM

I claim the ornamental design for a transmitter for a motion sensor, as shown and described.

DESCRIPTION

FIG. 1 is a isometric view of my design.

FIG. 2 is a front view of my design.

FIG. 3 is a bottom view of my design.

FIG. 4 is a top view of my design; and,

FIG. 5 is a side view of my design, with the opposite side being a mirror image.

1 Claim, 5 Drawing Sheets

FIG. 1

FIG. 2

FIG. 3

FIG. 4

FIG. 5
